CLAIM

We claim the ornamental design for a thermal head for a printer, as shown and described.

DESCRIPTION

FIG. 1 is a rear perspective view of an embodiment of the claimed design;

FIG. 2 is a front perspective view of the claimed design of FIG. 1;

FIG. 3 is a bottom perspective view of the claimed design of FIG. 1;

FIG. 4 is a top view of the claimed design of FIG. 1;

FIG. 5 is a bottom view of the claimed design of FIG. 1;

FIG. 6 is a left side view of the claimed design of FIG. 1;

FIG. 7 is a right side view of the claimed design of FIG. 1;

FIG. 8 is a rear view of the claimed design of FIG. 1; and,

FIG. 9 is a front view of the claimed design of FIG. 1.

The ornamental design which is claimed is shown in solid lines in the drawings. The broken lines in the drawings are for illustrative purposes only and form no part of the claimed design. Broken lines formed by equal length dashes show unclaimed portions of the design. Broken lines formed of unequal length dashes show boundaries between claimed and unclaimed portions of the design.
